UNITED STATES PATENT OFFICE.

MILLARD F. WILFONG, OF PHILADELPHIA, PENNSYLVANIA.

ANNEALING-BOX.

No. 915,259.

Specification of Letters Patent. Patented March 16, 1909.

Application filed December 14, 1908. Serial No. 467,530.

To all whom it may concern:

Be it known that I, MILLARD F. WILFONG, residing at Philadelphia, in the county of Philadelphia and State of Pennsylvania, a citizen of the United States, have invented or discovered a certain new and useful Improvement in Annealing-Boxes, of which improvement the following is a specification.

The invention described herein relates to 10 certain improvements in annealing boxes.

Experience has shown that the riveted joints, where the sides and top are made of sections and united by rivets, will become loose and permit of the passage of gas or air, 15 such opening of the joints being due to the different percentage of expansion of the different sections, as a result of the difference of temperature to which the several parts of the box are subjected, when in use. Heretofore 20 the joints between the ends and sides have been formed by bending a flange on the head, the bend being sharp, so that the flange for its entire width will be at right angles to the head, which is so applied that 25 the flange will under-lap the sides and top of the box for practically the entire width of such flange. The rivets securing the head and body will be closely adjacent to the edges of the side and top plates and also to 30 the body of the head, thus forming a very rigid joint. During expansion and contraction the change of dimensions of the heads will be in directions practically parallel with the sides of the head, or radially. The 35 movement of metal in the sides and top will be in directions at an angle to the directions of enlargement of the head, and the joint between the head and sides and top being rigid, the rivets are strained and stretched, 40 permitting leakage.

The invention described herein has for its object an annealing box having its sides and top formed of a single sheet of metal.

It is a further object of the invention to 45 provide a yielding or flexible connection between the body and the ends of the box.

The invention is hereinafter more fully described and claimed.

In the accompanying drawings forming a 50 part of this specification Figure 1 is a view partly in side elevation and partly in section of my improved annealing box. Fig. 2 is a bottom plan view of the same; Fig. 3 is an end elevation illustrating a modification, and 55 Fig. 4 is a sectional elevation of one end of the box constructed as in Fig. 3.

In the practice of my invention the sides 1 and top 2 of the annealing box are formed by properly bending a single sheet or plate of metal, the top being either circular or flat, 60 as desired. The sides and top are internally braced, preferably as shown and described in an application filed by me July 7, 1908, Serial No. 442,364, such braces consisting of angle irons 3 riveted to opposite 65 sides of a metal strip 4 and also riveted to the inner faces of the top and sides. The filling piece 4^a for strengthening the top forms a chord for the arched top and strengthens the same vertically and transversely.

The ends of the box may be formed of single sheets of metal properly dished or bent so as to form head 6 and flanges 5 of considerable depth, which, as shown, are riveted to 75 the ends of the body the flange and head being connected by the yielding portion 7. Heretofore in bending the edges to form the flanges on the sheet the bends were sharp, having a radius of curvature not materially 80 greater than the thickness of the metal, and hence such curved portions form rigid and unyielding connections between the flange and the head 6 of the ends. In lieu of such short, sharp bend, the flange and head are 85 connected in my improved end by metal bent to a curvature having a comparatively large radius, the curved connecting portion 7 gradually merging into the straight portions of the head and flange which is parallel with the 90 body of the box, as clearly shown. These gradually curving portions form a yielding or flexible connection between the body of the box and the end plates, and by reason of such flexibility injury to the joints between the 95 head and body due to different rates or amount of contraction and expansion, is prevented. As shown in Figs. 1 and 2 the head 6, flange 5 and connecting portion may be formed of one plate. But if preferred, the 100 flange and connecting portions may be formed by properly bending a strip of metal, and the head 6 of the end riveted to such bent piece, as shown in Figs. 3 and 4.

It is characteristic of my improved box 105 that as the sides and top are formed without joints of any kind and the end is so connected to the body of the box that the joint between is not subjected to injurious strains, all liability of leakage is practically eliminated. 110

I claim herein as my invention:

1. An annealing box having a body por-

tion, heads, and yielding portions or members connecting the heads to the body portion.

2. An annealing box having sides and top formed integral with each other, heads, and yielding portions or members connecting the heads and body portion.

3. An annealing box having sides and top formed integral with each other, heads and

yielding portions or members for connecting the heads to the body portion and formed integral with the heads.

In testimony whereof, I have hereunto set my hand.

MILLARD F. WILFONG.
